UNITED STATES PATENT OFFICE.

GEORGE W. STANCLIFF, OF HOUSTON, TEXAS.

WIRE-WINDING MACHINE.

No. 854,541.

Specification of Letters Patent.

Patented May 21, 1907.

Application filed December 15, 1906. Serial No. 348,045.

To all whom it may concern:

Be it known that I, GEORGE W. STANCLIFF, a citizen of the United States, residing at Houston, in the county of Harris and State of Texas, have invented a new and useful Wire-Winding Machine, of which the following is a specification.

This invention relates to wire winding machines and is particularly designed for manufacturing well screens of the type composed of wire wound around a section of perforated tubing and spaced from the latter by means of a plurality of ribs, an example of this class of screens being found in the patent issued to me on the 18th day of October, 1904, No. 772,843.

Among the objects of the present invention are to provide a wire winding machine of simple and improved construction whereby wire may be wound spirally around a body, which latter is supported for rotation.

A further object is to form seats or notches within the ribs for the reception of the wire coils.

With the above and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of the complete machine; Fig. 2 is a plan view thereof; Fig. 3 is an elevation showing the power transmitting mechanism at the power end of the machine; Fig. 4 is a section on line $x-x$ Fig. 2; Fig. 5 is a section on line $y-y$, Fig. 2; Fig. 6 is a section on line $z-z$, Fig. 4; Fig. 7 is an enlarged view partly in elevation and partly in section of the chuck cone and showing one end of a tube thereon; Fig. 8 is a detail view of the securing yoke or cam; Fig. 9 is a similar view of the sectional nut adapted to engage one of the feed screws; and Fig. 10 is a detail view showing in elevation the hangers carrying the sectional nuts, the strips between which said hangers are mounted being shown in section.

Referring to the figures by characters of reference, A is a suitably constructed frame preferably formed of angle iron and provided adjacent one end with a cross strip 1. A pair of feed screws 2 and 3 extend longitudinally of the machine, the screw 2 bearing at its ends within the cross strip 1 and one end of the frame while the screw 3 extends

throughout the length of the frame and is mounted in bearings at the ends thereof. Each screw carries upon one projecting end a sprocket 4 and mounted on these sprockets is 60 a chain 5 which serves to transmit rotary motion from one to the other. A power shaft is journaled in the opposite end of the frame A and in the cross strip 1 and carries a cone pulley 7 and a drive gear 8. This gear 65 meshes with a larger gear 9 secured on a shaft 10 journaled within the cross strip 1 and the adjoining end of the frame and has an outer sprocket 11 and an inner sprocket 12 secured to it. A chain 13 is arranged on the sprocket 70 11 and serves to transmit rotary motion to a sprocket 14 which is secured upon the adjoining end of the screw 3.

A shaft 15 having a longitudinal slot 16 therein is journaled adjacent its ends in a 75 bearing 17 extending inward from one side of the frame and in the cross strip 1 and this shaft carries a sprocket 18 which receives motion from the sprocket 12 through a chain 19. A track is formed upon the inner or adjoining faces of the sides of frame A and consists of longitudinally extending channel beams 20 and mounted on this track is a tail carriage B consisting of a rectangular frame 21 the opposite portions of which bear on the 85 track 20 while an adjusting screw 22 extends longitudinally of the center of the carriage and is adapted to be rotated by a hand wheel 23—or in any other preferred manner. This screw carries a collar 24 from which projects 90 a stem 25 and rotatably mounted on this stem is a hollow cone 26. Balls or other friction reducing devices 28 are interposed between the collar 24 and the core 29 of the cone. A cross strip 30 connects the sides of 95 the carriage B and engaging this cross strip is an adjusting screw 31 adapted to be operated by a hand wheel 32. This cross strip engages a clamping plate 33 which extends under the beams 20 so that by turning the 100 screw 31 said clamping plate and the carriage can be forced tightly against opposite faces of the beams 20 so as to hold the carriage against movement after it has once been adjusted to a desired point upon the track. 105 By means of the screw 22 the cone 26 can be adjusted longitudinally of the machine independently of the carriage. Another cone 34 similar to the cone 26 is mounted on the inner end of the shaft 10 hereinbefore referred to, and this cone constitutes a chuck member 110 and the same is provided with one or more

slots 27 adapted to receive suitable tube securing clamping yokes which will be herein-after referred to. The longitudinal axes of the two cones are in alinement and parallel with the feed screws 2 and 3.

Secured upon the sides of the frame A are upstanding rails 35 and slidably mounted on these rails are supporting blocks 36 on which is mounted the frame C of the main carriage. 10 This frame consists of a suitable arrangement of uprights 37, top beams 38 and bottom beams 39, all of said beams being rigidly connected. The lower beams 39 are preferably arched over the longitudinal center of the machine as shown at 40 and the upper beams 15 38 are connected by parallel cross beams 41 while the lower cross beams 39 are connected directly under the beams 41 by parallel guide strips 42. Secured to the inner strips 42 and 20 to the inner faces of the cross beams 41 are guide standards 43 connected at their upper ends by a cross strip 44. Slidably mounted between the guide standards is a sliding frame 45 supported by bolts 46 which extend 25 through the cross strip 44 and are engaged by adjusting nuts 47. This frame has cross strips 48 and 49 therein the cross strip 48 carrying a guide 50 within which is slidably mounted a series of plungers 51 each of which 30 has a recess 52 in one edge and into which projects a spring 53 which constitutes a cushioning support for the plunger. Another spring 54 bears upon the upper portion of each plunger 51 and serves to hold the plunger 35 normally in the position shown in Fig. 4. Secured to the cross strip 49 is a guide 55 and arranged within this guide is a series of chisels 56 one of which is disposed below each plunger 51. Each of the chisels has a notch 40 57 in one edge into which projects the end of a spring 58 and said spring serves to support the chisel as shown particularly in Fig. 4. The adjoining ends of the plungers and chisels are normally out of contact as indicated 45 in said figure. The cutting edges of the chisels 56 project into the arched portion of the frame C.

Arranged between each pair of guide strips 42 is a pair of hangers 59, said hangers being 50 spaced apart at their upper ends by a shaft 60 which is rotatably mounted within them and is provided at one end with a crank 61 while a cam 62 is connected to its other end. This cam bears upon one of the strips 42. 55 Located between the lower ends of the standards and connected to them are threaded blocks 63 which are adapted to rest on and engage the screws 2 and 3. The guide strips 42 are preferably provided with guide pins 60 64 which project into slots 65 formed in the hangers 59 so that said hangers will be maintained vertical at all times.

It will be understood that the blocks 63 will engage the screws 2 and 3 by gravity so 65 that when said screws are rotated the blocks

and the entire carriage C connected to them will be moved longitudinally of the machine and by partly rotating the cranks 61 the cams 62 will be forced downward against the strips 42 thereunder so as to raise the hangers 59 70 and lift the blocks 63 from engagement with the screws 2 and 3.

Standards 66 are mounted on the cross strip 48 of the sliding frame 45 and support a shaft 67 carrying a sprocket 68. A chain 75 69 extends over this sprocket and under a sprocket 70 which is feathered on the grooved shaft 15. Tappet mechanism consisting of a series of disks 71 equal in number to the plungers 51 is keyed on the shaft 67 and each 80 disk has two oppositely extending teeth 72 extending therefrom the teeth of the disk being disposed out of alinement. Each plunger 51 has a shoulder 73 upon that face thereof facing the disks 71 and the teeth 72 85 are adapted to swing upward against the shoulders and lift the plungers against the action of springs 54. The teeth 72 are so arranged that a tooth of one disk 71 will raise the first plunger 51 and as soon as said 90 plunger is dropped a tooth of the next disk will raise the second plunger and this operation will be continued and repeated indefinitely as long as the disks 71 rotate.

A supporting plate 74 is suitably secured 95 to one of the standards 43 and carries a plurality of grooved rollers 75 which are disposed out of alinement and which constitute a tensioning device for a wire 76. This wire is adapted to be unwound from a spool located at any suitable point and passes from said spool to the tension rollers 75 over a grooved wheel 77 carried by one side of the frame C and under another grooved wheel 78 located at the lower end of an arm 79 100 105 which is secured to and hangs downward from the front of the frame C.

In using this machine the tube 80 to be wrapped with wire is placed with one end upon the cone 34 after which the carriage B 110 is adjusted toward the adjoining end of frame A so as to permit the tube to be placed in front of the cone 26 whereupon the carriage is adjusted toward the tube so as to force the cone thereinto. Said carriage is 115 then clamped in place by means of the screw 31 and plate 33 after which the cone 26 is pushed forward farther into the tube by means of the screw 22. The tube is then locked to one of the cones by fastening a tube 120 clamping member in the form of a yoke 81 thereto by means of a set screw 82 and the free end of said yoke will project into the slot 27 in the cone thereunder. After the tube has been secured in place in this manner 125 the cranks 61 are swung so as to raise the blocks 63 from engagement with the screws 2 and 3 whereupon the entire carriage C is slid along the rails 35 until it is in position over one end of the tube. The blocks 63 130

are then lowered into engagement with the screws 2 and 3. The wire from the spool is threaded under the wheel 78, over the wheel 77 and between the tension wheels or pulleys 75 and is then fastened to one end of the tube directly in rear of the chisels 56. Power is then applied to the drive shaft 6 and by reason of the gearing which has been described the tube will be rotated by the cone 34, the grooved shaft 15 will also be rotated and the screws 2 and 3 will be revolved simultaneously. These screws will move the carriage C slowly along the rails 35 while the grooved shaft 15 will rotate sprocket 70 and cause the shaft 67 and the disk 71 thereon to revolve. The teeth on the disks will successively raise the plungers 51 against the tension of their springs 54 and when they are dropped these plungers will spring downward against the chisels 56 and drive them into the ribs 83 which are arranged upon the tube 80. The chisels are adapted to successively strike the ribs so as to form notches therein at proper points to receive the wire, which wire is wound on the tube as the same is rotated and as the carriage travels forward. The chisels can be adjusted so as to act upon tubes of different diameters simply by raising or lowering the slidable frame 45. The preferred form of the invention has been set forth in the foregoing description but I do not limit myself thereto as I am aware that modifications may be made therein without departing from the spirit or sacrificing the advantages thereof, and I therefore reserve the right to make such changes as fairly fall within the scope of the claims.

What is claimed is:

1. In a wire winding machine, a chuck for engaging a tubular body and consisting of a conical member having a longitudinal groove, a tube receiving member slidable in said groove, and means carried by said member for clamping upon a tube.
2. In a wire winding machine, a longitudinally grooved conical chuck, a tube receiving yoke slidable in the groove, and means carried by the yoke for engaging a tube.
3. In a wire winding machine, a conical chuck having a longitudinal groove in the face thereof, a yoke slidable in said groove, and a set-screw in the free arm of said yoke.
4. In a machine for winding wire about tubular bodies, a tube engaging chuck consisting of a conical member having longitudinal grooves in the face thereof, tube engaging yokes slidable in said grooves, and set screws extending through the free arm of the yokes.
5. In a machine of the class described for winding wire about tubular bodies, a driven shaft having a conical chuck member, tube engaging clamps adjustably engaging said chuck member, an adjustable tail carriage, a screw operating in said tail carriage in axial

alignment with the chuck carrying shaft, and a conical tube engaging member swiveled upon said screw.

6. In a machine of the class described, means for supporting and for imparting rotary movement about its axis to a tubular member, a carriage supported for movement parallel to the axis of the supported tubular member, a wire support connected with the carriage, and a tension device connected adjustably with the latter.

7. In a machine of the class described, means for supporting and rotating a body about which wire is to be wound, a wire carrier movable parallel to the axis of rotation, and means supported by the wire carrier for forming wire receiving seats in the object about which wire is to be wound.

8. In a wire winding machine, a plurality of yieldingly supported chisels, a yieldingly supported plunger above each chisel, and rotatable means for successively lifting said plungers and releasing them to actuate the chisels.

9. In a wire winding machine, means for supporting and rotating an object about which wire is to be wound, a movably supported carriage, means for feeding the carriage in a direction parallel to the axis of rotation of the object about which wire is to be wound, wire carrying means supported upon the carriage, a frame adjustable in said carriage toward and from the object about which wire is to be wound, and a seat forming chisel movably supported in said frame.

10. In a wire winding machine, a carriage supported for movement parallel to the axis of rotation of the body about which wire is to be wound, wire supporting means upon said carriage, a frame adjustably supported upon said carriage, a seat forming chisel in said frame, a chisel engaging plunger in the frame, and means for intermittently operating the plunger.

11. In a wire winding machine, a carriage having a wire guiding and tensioning means, a frame adjustable in the carriage, a seat-forming chisel supported in the frame, a chisel-actuating plunger in said frame, a resilient support for the plunger, resilient means for exerting longitudinal pressure upon the plunger, tappet means for actuating the plunger, and means for transmitting motion to the tappet means independently of the movement of the carriage.

12. In a wire winding machine, a main frame, feed screws supported for rotation in the frame, a carriage, vertically movable members connected with the carriage, screw engaging devices movable with said members, and means for actuating the members to disengage said devices from the feed screws.

13. In a wire winding machine, a main frame, feed screws supported for rotation in the frame, a carriage, vertically movable

members connected with the carriage, screw engaging devices movable with said members, a shaft journaled within the members, means rotatable with the shaft for raising the shaft and members, and means for facilitating the manual rotation of the shaft.

14. In a wire winding machine, a main frame, a plurality of spring-supported seat-forming chisels, a spring-actuated and spring-supported plunger above each chisel and adapted to impact thereupon, and a series of

toothed disks rotatably mounted adjacent to and adapted to successively drop, the plungers to operate the chisels.

In testimony that I claim the foregoing as my own, I have hereto affixed my signature in the presence of two witnesses.

GEORGE W. STANCLIFF.
